UNITED STATES PATENT OFFICE.

GERALD E. OTIS, OF MOLINE, ILLINOIS, ASSIGNOR TO THE HERMAN NELSON CORPORATION, OF MOLINE, ILLINOIS, A CORPORATION OF ILLINOIS.

RADIATOR STRUCTURE.

Application filed July 2, 1923. Serial No. 648,916.

This invention relates to improvements in radiator structures for heating purposes, and having as its primary object the provision of a light, durable, compact, and efficient heating element.

Among the further objects of the invention is to combine certain novel features of construction, calculated to decrease the weight and size of a radiator, by employing a more effective method of heat transmission and characterized by a single hollow core of substantially uniform shape through which the heating fluid is circulated, together with a plurality of metallic plates or flanges applied to the surface of the central core and forming secondary heating elements.

The principle underlying the practice to be followed in utilizing the invention is, that the transmission of heat efficiently from a primary heating element or hollow core, to the secondary elements in the form of plates or flanges, is dependent largely on the intimacy of the contact between the elements. It is conceived that ordinary bearing contact between two metallic surfaces is not productive of efficient heat transmission, by reason of the unavoidable presence of minute air spaces or gaps which interrupt the flow of heat from one to the other in much the same manner as an air gap will effectively restrict or interrupt the flow of electricity from one conductor to another.

It follows, therefore, that the means utilized for applying the secondary elements is of importance, and suggests also the utilization of the same means for controlling the effective heating capacity of any radiator by regulating the contact between the secondary heating elements and the central core.

A further object of the invention is to provide a radiator designed to afford greater efficiency than the more common form cast-iron radiator of the sectional type generally used for heating purposes. Such radiators are massive and of great weight and, therefore, open to objections for these reasons as well as for the fact that the sectional construction affords possibility of leakage and inefficient circulation of the heating fluid. As the heating element of heating and ventilating apparatus, the common sectional radiator is particularly unsuited for the purpose since the entire apparatus must necessarily be designed to accommodate the massive radiator, and hence the size and space occupied is often

a material objection to the otherwise advantageous use. Moreover in the matter of manufacture and installation, the use of the cast metal sectional radiator is objectionable in that it must ordinarily be shipped separately from the remaining parts of the apparatus and assembled at the place of installation. By the use of a relatively light and compact radiator, the unit can be designed to occupy a much smaller space, and otherwise constructed as a self-contained device for shipment to the place of installation.

Other objects and advantages of the structure embodying the invention will be alluded to in the following description in connection with the accompanying drawings, wherein:

Figure 1 is a view in side elevation of a single radiator unit with portions broken away to show more clearly the construction.

Figure 2 is an enlarged detail view in horizontal section through one end portion of the radiator unit as taken on line 2-2 of Figure 1.

Figure 3 is view similar to Figure 2, showing a radiator with an additional layer of secondary elements, and

Figure 4 is a detail view in vertical section taken on line 4-4 of Figure 3.

The radiator in its simplest form consists of an elongated central core 1, shown as mounted in vertical position and having secondary heating elements 2, 2 in the form of corrugated plates bent in zig-zag form or connected series of V-shaped fins secured to the sides of said core, and outer plates 3, 3 secured against the corrugated plates 2, 2.

The central core is a hollow unitary container cast of a suitable corrosion resisting metal, designed to withstand the shocks and strains of expansion and contraction, and the abuses incident to handling and installation, but otherwise of as light a construction as practicable. In horizontal section the central core is shaped like an elongated I-beam having end portions 1^a, 1^a widened to substantially twice the width of the central or intermediate portion 1^b. At the ends of the central core are cast bosses 4, 4 into which are fitted the supply and return pipes 5 and 6 respectively, for the heating fluid, the former being located near the top and the latter near the bottom of the core.

As clearly shown in Figure 2 the secondary heating elements 2, 2 are, as already suggested, in the form of corrugated plates which may

be regarded as a multitude of alternately inverted and connected V-shaped elements having a flattened face 2^a at each apex bearing against the side of the central core and the plates 3, 3. The stock from which the plates 2, 2, are made is preferably a light gauge metal of relatively high heat conductivity, such as aluminum or copper.

In width or vertical dimension these corrugated plates 2, 2 are equal to that of the core. Longitudinally the plates 2, 2 extend the full length of the core between the end portions 1^a, 1^a. Covering the corrugated plates are the outer plates 3, 3 the same being flat and uncorrugated, and of slightly increased thickness, and hence somewhat stiffer. These outer plates extend throughout and completely cover the corrugated plates, and are not only held in place but are clamped against the outer flattened faces of the corrugated plates, by means of bolts 7, which are preferably located in pairs spaced apart, one above the other, and distributed at suitable distances apart throughout the length of the structure. At the points where the bolts are located, aligned recesses or depressions 8 are formed in the outer plates, the bolts extending through central apertures therein, and cored holes 9, extending transversely through the central core 1. To accommodate the depressions as well as the bolts, portions of the corrugated plates 2 are cut away, as clearly shown in Figure 2.

The outer plates and bolts provide clamping members serving to force the corrugated plates in close and intimate contact with the core, as well as with the outer plates themselves, through the medium of the flattened faces 2^a, thus establishing the necessary degree of contact to eliminate any spaces or gaps between the contacting surfaces due to any roughness or unevenness that may exist. If desired, cement, solder, or paste made of copper filings may be used as filling substance between the contacting surfaces, thereby increasing the conductivity, although the application of pressure is ordinarily sufficient to insure effective heat transmission. Due to the pressure applied by the bolts 7, it is at once manifest that the outer plates shall be sufficiently heavy to resist distortion or warping, and to thus effect a uniform distribution of the pressure throughout the entire area of the corrugated plates.

In this type of radiator structure, the top and bottom surfaces are open so that a multitude of vertical air passages are formed between the corrugated plates, the central core and outer plates 3, 3. Thus the air to be heated may circulate or be forced, as the case may be, through the radiator and into contact with the entire heating area.

Obviously the heat of the steam or other heating fluid supplied to the radiator is absorbed by the walls of the core 1, and thence

transmitted rapidly and without retardation or loss to the corrugated plates and finally to the outer plates, this heat being ultimately dissipated to increase the temperature of the air passing through the radiator.

Figures 3 and 4 illustrate a further development of the construction already discussed, wherein two layers or thicknesses of corrugated plates are employed instead of one.

So far as the central core 1 and the adjacent corrugated plates are concerned, the structure is built up in the same manner as before. The departure therefore resides in applying additional corrugated plates 10, 10, over the inner corrugated plates 2, 2, with an intermediate plate or sheet 11, separating the two. The positioning of the two adjacent pairs of corrugated plates is preferably such that the adjacent flattened faces 2^a and 10^a bear against the intermediate sheet 11, at points on opposite sides thereof, thus establishing a direct path for the heat from the core in an outward direction. The outer plates 3, 3 are the same as before except that they are spaced further from the central core, and bear against the outer corrugated plates instead of the inner plates 2, 2. For this reason also, longer bolts 12, 12 are used but otherwise the structure and assembly is duplicated.

The structure of Figures 3 and 4 is capable of heating a greater volume of air, but not perhaps capable of raising the temperature to the same degree. This suggests that such a structure would be advantageous under conditions where a greater volume of air is handled, but the heating of the air to a high temperature is not necessary. These are conditions that ordinarily exist in mild climates or during mild weather.

A feature of this structure for radiators, as typified by either of the two forms shown, is the possibility of controlling the heating capacity by varying the pressure exerted upon the contact faces of the secondary heating elements, bearing in mind that the effective transmission of heat is largely dependent upon the intimacy of contact between the faces, it is at once manifest that by decreasing the pressure by loosening the bolts 7 (or 12) the contact will be proportionately reduced and the heat transmission in like proportion. Thus the same radiator may be adjusted to meet varying heating requirements without cutting down the volume of the air delivered through the radiator or the apparatus of which it forms a part. Apart from the control of the heating capacity of the structure, and the efficiency that may be obtained, it offers other advantages, some of which have been mentioned. The single core does away entirely with the sectional construction that is common in heating radiators and the numerous joints and seams with

the attendant opportunity for leakage. Furthermore in the use of a core having a single fluid compartment, the difficulties of circulating the heating fluid and the venting of the 5 trapped air are not present.

Having therefore presented a preferred embodiment of the invention and with the understanding that it is not limited to the precise disclosure herein, I claim as my invention:

1. In a radiator structure, the combination with a hollow metal core having substantially rigid walls presenting flat outer surfaces; of a plurality of sheet metal heat-transmitting elements extending transversely from the heating surfaces of said core and having elongated contact faces engaging said flat outer surfaces; and means for holding all of said elements on the core under pres-

sure to bring the contacting faces thereof 20 into intimate contact with the said core surfaces.

2. In a radiator structure, the combination with a single hollow cast metal core having relative large flat heating surfaces on opposite sides thereof; of heat-radiating plates of sheet metal mounted on said core, said plates having core-contacting elements and heat radiating elements forming a cellular structure adjacent the heating surfaces of said core; and a tie member for holding the plates on the core and maintaining the plates compressed to force said core-contacting elements thereof into intimate contact with the flat surfaces of the core.

In witness whereof, I hereunto subscribe my name this 2nd day of June, A. D. 1923.

GERALD E. OTIS.
